IGNITER FOR OIL STOVES

Alfred Ruttiman, Gardner, Mass., assignor to The Alaska Freezer Co. Inc., Winchendon, Mass., a corporation of Massachusetts

Application October 6, 1932, Serial No. 636,587

10 Claims. (Cl. 175—115)

This invention relates to igniters and more particularly to an igniter of the jump spark type adapted for use with oil burning stoves.

An object of this invention is to provide an igniter which may be rigidly supported within the burner base of the stove without danger of oil leakage and which may be readily removed therefrom for replacement or cleaning.

Another object of the invention is to provide an igniter so constructed that fouling at the spark-gap is minimized.

A further object of this invention is the provision of a lead wire insulator which prevents current losses to the igniter.

15 Other objects of the invention will appear from the following description.

A preferred embodiment of the invention is shown in the accompanying drawing, in which:

Fig. 1 is a plan view of a burner having the 20 igniter secured therein.

Fig. 2 is an elevation in section of Fig. 1.

Fig. 3 is a section on the line 3—3 of Fig. 2.

Fig. 4 is a fragmentary sectional view of a modified form of igniter locking means.

25 Fig. 5 is an enlarged sectional view of the igniter alone.

Fig. 6 is a plan view of Fig. 5.

Fig. 7 is an elevation of the igniter provided with a second insulator.

30 Fig. 8 is a plan view of Fig. 7.

Fig. 9 is a sectional elevation of a modified form of igniter showing the improved locking means applied thereto.

Fig. 10 is a longitudinal sectional view of a 35 plurality of lead wire insulators.

The burner base 11 has the usual annular trough 12 formed in its upper face for the reception of the kindler 13. Oil is supplied to the trough 12 to saturate the kindler 13, through the 40 pipe opening 14, the supply pipe not being shown.

Projecting upwardly from the base of the trough 12 is a boss 16. This boss interrupts the continuous circularity of the kindler 13 and extends above the maximum level which the oil 45 within the trough may attain. On the under side of the base 11 and in axial alinement with the boss 16, is a depending boss 17.

The bosses 16 and 17 are bored at 18 and since the top opening to this bore is well above the oil 50 level in the trough, leakage of the oil therethrough is precluded.

Adapted for insertion within the bore 18 is the insulator 19 of the igniter. Preferably, this is a loose fit, whereby a space will exist between the 55 insulator and the side of the bore through which

air may flow to assist in burning off carbon accumulation on the upper portion of the insulator. A longitudinally cut away portion shown at 35 extending nearly the entire length of the insulator provides a larger passageway to increase 60 this flow of air.

The insulator may be of porcelain or similar material and has a reduced portion at 20, forming a head 21. The reduced portion also provides an air space between the insulator and the 65 boss 16 and increases the length of travel and resistance to current leakage along the outside of the insulator.

The insulator is axially apertured as shown in Fig. 5 to receive an electrode 22. This electrode is 70 preferably a single wire which is bent double and passed through the aperture in the insulator; the loop 23 remaining outside the insulator to constitute a terminal for the lead wire 24. The upper ends of the electrode wire, where they emerge 75 through the head 21, are bent to extend laterally from the electrode.

To facilitate this bending, the head 21 may be radially slotted as shown at 25 and later be filled with a suitable insulating cement. By this 80 provision of a radial slot which may later be filled with cement it will be apparent that the rigidity of the free end of the electrode is considerably increased. The end will be supported up to the point where it emerges from the side of 85 the insulator.

Practical use of the device has shown that best 90 results are obtained when the ends of the wires are tapered. Preferably the ends of the wire are diametrically flattened to form a sharp knife edge as shown at 26. By forming the ends of the electrode wire in this manner, they may more quickly be raised to a high temperature sufficient to burn off any carbon or foreign matter accumulations which might short the igniter. The spark will then be 95 reestablished.

As shown in Figs. 7 and 8, an insulating bead 27 may be slipped over the ends of the electrode wire 22 where they project from the head 21, and retained thereon, by spreading the extending wire 100 ends. This bead will prevent the kindler 13 from contacting with the ends of the electrode wire and shorting the spark current.

Although the use of a single wire bent double is preferred, it is entirely possible to use an electrode made up of two or more individual wires. The upper end of these wires may be spread apart to retain the insulating bead 27 thereon, if desired. Further, a single wire may be used having its lower portion doubled upon itself to form the 110

loop while its upper portion is only a single strand presenting but a single terminal which may be flattened to a sharp edge as already described.

To retain the insulator within the bore 18, both 5 the insulator and the depending boss 17 may be formed with transverse registering slots 28 and 29. A locking wire 30 engaging with these slots and encircling the boss 17 as shown in Fig. 3 will prevent longitudinal movement of the insulator.

10 A modified means for retaining the insulator in place is shown in Fig. 4. The lower boss 17 is formed with a depending semicircular skirt 31. Secured to the skirt is a flexible locking finger 32 the free end of which engages with the transverse 15 slot 28 in the insulator. The skirt 31 also serves as a shield to prevent breakage of the frangible insulator.

This spring locking finger 32 serves not only as a means for retaining the electrode in place within 20 its support, against axial displacement, but it also holds the electrode against angular or turning movement in its socket. This is true also of the wire holding means first described. By holding means of this character the terminal points at 25 the spark gap will be held in their prescribed positions against displacement both vertically and angularly.

Furthermore, the holding means will tend to 20 press the insulator or body of the electrode against one wall of the socket to take up all looseness and at the same time provide the air passage along one side of the insulator plug from the bottom to the top thereof.

A further application of the locking means 25 shown in Fig. 3 is shown in Fig. 9. In this figure the burner base 36 has a threaded bore 37. The igniter comprises the usual insulator 38 and the retaining member 39 which is externally threaded at 40 to engage with the threads within the bore 37. The upper portion of member 39 forms a boss 41 projecting upwardly from the burner base, and the lower portion forms a boss 42 depending from the burner base. The lower boss provides a shoulder at 43 against which a gasket 44 of any suitable material may be compressed to prevent oil leakage through bore 37. If the engagement 45 of the threads on the member 39 with the threads within the bore 37 is sufficiently tight to prevent leakage the gasket 44 may be dispensed with.

To retain the insulator 38 within the retaining member 39, the insulator and the lower boss 42 are formed with transverse registering slots, 45 and 46 respectively, within which a locking wire 47 may be confined.

It may be pointed out that the only difference 50 between the structures shown in Figs. 3 and 9 is that in Fig. 3 the bosses 16 and 17 are formed integrally with the burner base whereas in Fig. 9 the corresponding bosses 41 and 42 are carried by the removable member 39. When the member 39 is in place, the structure produced is substantially the equivalent of that shown in Fig. 3.

It will be noted that the slot formed within the 55 insulator serves the additional function of indicating the proper positioning of the insulator within the bore which receives it. The user has merely to insert the insulator until the slot in the insulator coincides with the slot in the boss or with the flexible finger 32 sprung into place, to 60 know that the insulator is properly placed to provide the correct spark gap.

The form of insulator 52 shown in Fig. 10 is 65 particularly desirable to provide the best possible protection against shock or stray sparks. This insulator is a substantially tubular member having

a conical bore 53. The end having the smaller opening is spherically rounded as at 54 and the opposite end is spherically recessed as at 55. Extending beyond the spherically recessed end 55 is a conical flange 56.

If contiguous insulators are angularly displaced, as insulators 49 and 50 of Fig. 10, the larger opening of the bore will permit sufficient lateral movement of the lead wire 24 to prevent its binding at the junction. Similarly, the co-operating 80 spherical surfaces of contiguous insulators will maintain a surface contact and cracks will not be formed at the junctions when the wire 24 is curved. The flange 56 serves to insure that foreign matter does not enter the junction between the insulators. 90

The insulator 51 shown in Fig. 2 is bored to completely enclose the lower boss 17 and a portion of the first insulator 52, to protect these parts.

What is claimed is:

1. The combination with an oil burning stove 95 having a burner base and a kindler supported therein, of an igniter comprising an insulator, an electrode within the insulator, the upper end of said electrode extending beyond the insulator and close to the kindler, and to a point to provide 100 a spark gap adjacent the kindler to ignite the oil on the kindler, and a second insulating member carried by the upper extending end of the electrode to prevent the kindler contacting with the electrode.

2. The combination with an oil burning stove having a burner base and a kindler supported therein, of an igniter comprising an insulator, a spark electrode within the insulator, the upper end of said electrode extending laterally beyond 110 the insulator and above the kindler to provide a spark gap adjacent the kindler therein to ignite the oil on the kindler, and a second insulating member carried by the upper laterally extending end of the electrode where it passes above the 115 kindler to retain the kindler and electrode in spaced relation.

3. The combination with an oil burning stove having a burner base and a kindler supported therein, of an igniter comprising an insulator 120 to be carried by said base, an electrode within the insulator, said electrode having two or more wires the upper ends of which extend beyond the insulator close to the kindler, and to within close proximity with the burner base to provide spark 125 gaps adjacent the kindler therein to ignite the oil on the kindler, and a second insulator carried by the upper extending ends of the electrode wires to prevent the kindler contacting with the electrode, the portions of the said ends projecting 130 beyond the second insulator being separated to retain the second insulator in place.

4. The combination with an oil burning stove having a burner base and a kindler supported therein, of an igniter comprising an insulator to 135 be carried by said base, an electrode within the insulator, said electrode being a doubled wire, the upper ends of which extend laterally beyond the insulator and above the kindler to within close proximity with the burner base to provide 140 spark gaps adjacent the kindler therein to ignite the oil on the kindler, and a second insulator carried by the upper extending ends of the double electrode wire to prevent the kindler contacting with the electrode, the portions of the said ends 145 projecting beyond the second insulator being divergent to retain the second insulator in place, and being tapered to facilitate their heating to a high temperature to burn off carbon particles obstructing the spark gaps.

5. The combination in an oil burning stove of a burner base having a kindler therein, axially disposed bosses projecting from the upper and lower faces of the burner base, said bosses having 5 axial bores, an igniter comprising an insulator provided with a spark electrode, arranged within the bore through the bosses, said insulator having a transverse slot near its outer end, a depending skirt formed on the lower boss and laterally spaced from the insulator to protect the outer portion of the insulator, and a flexible locking member secured to the depending skirt and extending within the slot in the insulator to retain the insulator against longitudinal motion in either 10 direction. 15
6. The combination in an oil burning stove of a burner base having a kindler therein, axially disposed bosses projecting from the upper and lower faces of the burner base, said bosses having 20 axial bores, and an igniter of uniform contour comprising an insulator and an electrode, arranged within the bore through the bosses, said electrode extending to a point to provide a spark gap adjacent the kindler to ignite the oil thereon, 25 said insulator having a transverse slot to register with a retaining member to indicate the proper positioning of the insulator within the bore whereby the proper spark gap will be provided. 30
7. The combination in an oil burning stove of a burner base having a kindler therein, axially disposed bosses projecting from the upper and lower faces of the burner base, said bosses having axial bores, and an igniter comprising an insulator and an electrode, arranged within the bore 35 through the bosses, there being a longitudinal space between the insulator and the side of the bore throughout the length of the bore to provide a passageway for supplying air along the insulator from the outer side of the burner base to the upper portion of the insulator whereby carbon deposits thereon will be burned off. 40
8. The combination in an oil burning stove of a burner base having a kindler therein, axially disposed bosses projecting from the upper and lower faces of the burner base, said bosses having axial bores, and an igniter comprising an insulator and an electrode, arranged within the bore through the bosses, said insulator having a loose fit within and throughout the length of said bore, and means for holding the insulator in place against one wall of the bore to provide a passageway alongside the insulator for supplying air to the upper portion of the insulator whereby carbon deposits thereon will be burned off. 80 85
9. In combination, a burner base, a kindler supported therein, an igniter comprising an insulator, an electrode having its upper portion extending from said electrode and having its end deformed, and a second insulating member carried by the projecting end of the electrode to prevent the kindler contacting the electrode, said second insulating member being retained on the electrode by the deformed end portion thereof, substantially as described. 90 95
10. The combination with a burner base having an annular trough with a kindler therein, and an aperture opening into the trough, of an igniter arranged within said aperture and comprising an insulator of uniform contour and an electrode, said electrode extending laterally from the igniter to a point to provide a spark gap adjacent the kindler to ignite the oil thereon, said insulator having a transverse slot with a non-concentric base, and a retaining member carried by the base to register with the slot and thereby determine the lengthwise positioning of the insulator within the aperture, and said retaining member engaging against said non-concentric base to determine the proper angular position of the insulator about its longitudinal axis and point the laterally extending electrode in the proper radial direction. 100 105 110 115
